Patented Aug. 25, 1914.

UNITED STATES PATENT OFFICE.

ERNEST D. SIMONS, OF WATERBURY, CONNECTICUT, ASSIGNOR TO SCOVILL MANUFACTURING COMPANY, OF WATERBURY, CONNECTICUT, A CORPORATION OF CONNECTICUT.

REEL-FIXTURE.

1,108,855.

Specification of Letters Patent. Patented Aug. 25, 1914.

Application filed January 12, 1914. Serial No. 811,637.

To all whom it may concern:

Be it known that I, ERNEST D. SIMONS, a citizen of the United States, residing at Waterbury, in the county of New Haven and State of Connecticut, have invented a certain new and useful Improvement in Reel-Fixtures, of which the following is a full, clear, and exact description.

Narrow fabrics, or woven narrow ware, such as elastic fabrics, braid, ribbons, tape and the like, are furnished to dealers on spools, blocks, or reels, and the last have been made so that the fabrics may be wound and unwound as desired. The winding apparatus comprises, in general, a spool, usually of wood, on which one end of the fabric is fixed in such way that by turning the spool the fabric will be wound upon it. Sides of appropriate diameter are arranged upon opposite heads of the spool to confine the wound fabric thereon and protect it while being handled, and the spool and sides have been connected to form the reel, by means of fixtures, so-called, which fixtures serve the additional purpose of winding or reeling means operable at pleasure.

The present invention relates to such fixtures, and it consists of eyelet-like metal members or parts having tapering barrels provided on their proximate ends with laterally extending teeth or prongs which are driven into the spool by expanding the barrels within a hole in the spool so as to unite the spool, sides and fixtures. One of the metal parts may have a bail connected with it to serve as a handle for turning the spool to wind the fabric, as I will proceed now to explain and finally claim.

In the accompanying drawings illustrating the invention, in the several figures of which like parts are similarly designated, Figure 1 is a perspective view of a reel. Fig. 2 is a diametrical cross-section, on a larger scale, with the sides broken away. Fig. 3 is a cross-section of one of the metal parts detached, Fig. 4 is an edge elevation, and Fig. 5 is a rear elevation thereof. Fig. 6 is a cross-section of the other metal part detached, Fig. 7 is an edge elevation, and Fig. 8 is a rear elevation thereof. Fig. 9 is a diametrical cross-section on the scale of Fig. 2, showing the parts in position to be assembled and before the metal parts are

expanded into fixed engagement with the 55 spool. Fig. 10 is a side elevation of a modification wherein the bail is omitted. Fig. 11 is a cross-section of another modification wherein the shoulder is omitted.

The wooden or other penetrable spool or 60 core 1, of circular contour and of a width or thickness approximately the same as the fabric it is to receive, has a central hole 2, and also has any suitable provision, such as a radial notch 3 indicated by the trans- 65 verse dotted line in Figs. 2 and 9, to engage the inner end of the fabric to be reeled or packaged. 4 indicates the sides, of cardboard or other suitable material.

The reel fixtures for uniting the spool or 70 core and the sides in such way that the said spool or core may be rotated between the sides, comprise similar metal members or parts 5 and 6, of eyelet-like formation. The part 5 has the flange or head 7, of any suit- 75 able contour, which may be provided with the sockets 8 to receive the bent-in ends 9 of a bail or handle 10 by which the spool is rotated; or, as shown in Fig. 10, this part 5' may be provided with a flange or head 80 7' without a bail or handle; and in such case any suitable provision may be made for turning the spool. In either case the part may be provided with the shoulder 11 to cause the flange or head to stand off from 85 the spool sufficiently to receive the adjacent side 4; but as shown in Fig. 11 the shoulder may be omitted from both parts of the fixture. The tapering barrel 12 terminates in laterally extending teeth or prongs 90 13. The part 6 likewise has a flange or head 14, a shoulder 15 (although this shoulder may be omitted, as just stated and as shown in Fig. 11,) and a tapering barrel 16 having the laterally extending teeth or 95 prongs 17.

The modifications shown in Figs. 10 and 11 represent both parts of the fixtures, or in other words, both parts of the fixtures of these modifications are alike.

As shown in Fig. 9, the parts are assembled by placing the spool centrally between the sides so that the holes 18 in the sides will register with the hole 2 in the spool; then the fixture parts 5 and 6 are inserted 105 in these holes from opposite sides so that their toothed barrels will approach one another within the hole in the spool, but so

separated as to leave the spool free to be turned or rotated between the sides, and then by means of a suitable expanding tool, the barrels are expanded from a taper to a cylindrical form, thereby driving the teeth or prongs 13 and 17 into the wall of the hole 2 in the spool, as shown in Fig. 2, and so securing the several parts together, and in such way that the spool may be rotated between and independently of the sides to wind the fabric upon it and permit unwinding of the same. The handle swings freely in the sockets 8 so as to gravitate into the position shown in Figs. 2 and 9 against the adjacent side, and so as to be capable of being turned out into position of use, as shown in Figs. 3, 4 and 5. The parts 5 and 6 may be made of thin sheet metal, substantially as eyelets or gromets are made, and produced economically. The simplicity of application of the fixture is a main advantage of the invention.

What I claim is:—

1. A reel fixture, adapted to connect the winding spool and the sides of a reel for packaging narrow fabrics and permit the winding and unwinding of such fabrics on such reel, comprising similar eyelet-like parts or members, each having a flange or head and a barrel provided with laterally extending teeth adapted to be expanded into permanent engagement with the spool.

2. A reel fixture, adapted to connect the winding spool and the sides of a reel for packaging narrow fabrics and permit the winding and unwinding of such fabrics on such reel, comprising similar eyelet-like parts or members, each having a flange or head and a barrel provided with laterally extending teeth adapted to be expanded into permanent engagement with the spool,

and an operating medium applied to one of the members.

3. A reel fixture, comprising similar eyelet-like parts or members, each having a flange or head and a tapering barrel provided with laterally extending teeth, combined with a spool, the barrels adapted to be expanded so as to embed their teeth permanently in the spool to effect the application of the fixture to the reel.

4. The combination with the sides and an interposed spool provided with aligned holes, of a reel fixture composed of similar eyelet-like parts having barrels provided with laterally extending teeth permanently forced into the wall surrounding the hole in the spool, and exterior flanges engaging the sides.

5. The combination with the sides and an interposed spool provided with aligned holes, of a reel fixture composed of similar eyelet-like parts having exterior flanges engaging the sides and longitudinally tapering barrels terminating in laterally projecting teeth, these barrels inserted in the hole in the spool at opposite ends and expanded therein to thereby drive their teeth permanently into the wall of the hole and thus unite the sides, spool and eyelet-like parts.

6. A reel fixture, comprising similar eyelet-like parts or members, each having a flange or head, a subjacent shoulder, and a barrel provided with laterally extending teeth.

In testimony whereof I have hereunto set my hand this 8th day of January A. D. 1914.

ERNEST D. SIMONS.
